UNITED STATES PATENT OFFICE.

FRANK F. FORSHEE, OF FLINT, MICHIGAN, ASSIGNOR, BY MESNE ASSIGNMENTS, TO WESTINGHOUSE ELECTRIC & MANUFACTURING COMPANY, OF EAST PITTSBURGH, PENNSYLVANIA, A CORPORATION OF PENNSYLVANIA.

CURLING-IRON PLUG.

Application filed June 3, 1921. Serial No. 474,730.

My invention relates to electrically heated devices and particularly to electrically heated curling irons and it has for one of its objects to provide a quickly detachable plug connector for use in curling irons and the like, which shall be simple and durable and which shall embody a relatively small number of parts.

Another object is to provide a plug connector of the above indicated character which shall operate as a swivel plug connector.

In practicing my invention, I provide a tubular casing of insulating material which has an axial opening therethrough of varying diameter. I provide a tubular insulating member which is adapted to be located in the axial opening of the tubular casing and mount inside of the tubular member a tubular resilient contact member which is adapted to be operatively engaged by a screw to which one conductor of the usual supply circuit may be connected.

I provide a pair of elongated, substantially flat resilient contact members which are located on the outside of the tubular insulating member and are clamped thereon and maintained at their outer ends in oppositely spaced relation by means of a ring-shaped member placed therearound intermediate their ends. A circumferential groove is provided around the tubular member located substantially beneath the ring-shaped clamping member to permit of resiliently clamping the elongated contact members of the tubular member.

One of the contact members clamped on the tubular insulating member has an integral longitudinal extension to which the other supply-circuit conductor may be connected.

I provide a loosely wound helical spring having an inner end turn of larger diameter than the other turns, surrounding the supply-circuit conductors immediately adjacent the outer end of the plug connector. I provide a cap, having an axial opening therethrough of a diameter to permit it to surround the helical spring and adapted, at its inner surface, to engage the enlarged end turn hereinbefore described, by means of

which the contact terminal structure is maintained in substantially its operative position in the axial opening in the tubular casing.

Referring to the single sheet of drawings:

Figure 1 is a view, partially in side elevation and partially in section, of the handle portion of an electrically heated curling iron, comprising the device embodying my invention;

Fig. 2 is a view, in lateral cross section, on the line II—II of Fig. 1, and

Fig. 3 is a view, in lateral cross section, on the line III—III of Fig. 1.

An electrically heated curling iron 1 comprises the usual tubular member 2 and a handle member 3, suitably secured thereto. The outer end of the handle 3 is provided with an axial opening 4 into which extend the usual contact members 5 and 6 of the electrical heating element (not shown). The two contact members are concentric and are insulated from each other by means of a tubular insulating member 7.

A plug connector 8, comprises a molded tubular casing 9 through which extends an axial opening of relatively large diameter at one end and of relatively small diameter at the other end. The inner end of the tubular casing 9 has a reduced outer diameter to permit of introducing it into the axial opening 4 in the handle member.

A tubular insulating member 10 is located substantially central of the length of the casing 9 and is provided with an axial opening 11, of circular cross section, extending therethrough. The diameter of the opening 11 is larger at its inner end than at its outer end, to provide a shoulder against which the outer end of a tubular contact member 12 fits. The contact member 12 is held in its operative position by means of a screw 13 engaging a threaded outer end portion thereof. The inner end portion may be slotted, as illustrated in Fig. 2.

A plurality of resilient elongated longitudinally extending and oppositely spaced contact members 14 and 15 are located on the outer surface of the tubular member 10. The members 14 and 15 are of arcuate form, in lateral cross-section, to conform to the

outer surface of the tubular member on which they are located. The member 14 extends outwardly only to the outer end of the member 10, while the member 15 has an integral outward turned-over extension 16 to provide sufficient thickness of material to mount a threaded connecting screw 17 therein.

The inner ends of the members 14 and 15 are bent inwardly to substantially V-shape to provide, in effect, a resilient notch which engages a circumferential groove provided in the contact member 6 to properly conduct current thereto, as well as to maintain the plug connector in its operative position, substantially as illustrated in Fig. 1.

In order to maintain the members 14 and 15 in their proper operative positions on the member 10, I provide a ring member 18 located adjacent one end of the tubular member and immediately over a circumferential groove 19 provided in the said tubular member. The dimensions and contour of the ring member 18 are such, that, in cooperation with the groove 19, the members 14 and 15 are resiliently clamped on the member 10.

The usual supply-circuit conductors 20 and 21 are provided, one of which has its end secured under the screw 17 to electrically engage the contact member 15 and the other of which has its end secured under the head of the screw 13, thus operatively engaging the tubular contact member 12.

In order to protect the supply-circuit conductors 20 and 21 against the injurious effect of repeated bending, I provide a helically wound spring member 22 having an inner diameter of helix sufficiently large to permit of passing the braided supply circuit conductors 20 and 21 therethrough. The spring member 22 is provided with an inner end turn of larger diameter than the others which is adapted to press against the outer flat surface of an insulating washer 23 through which the supply-circuit conductors 20 and 21 pass.

A cap member 24 has an axial opening 25 therethrough of a diameter sufficient to permit of locating the helical spring member 22 therein, the inner recessed surface of the cap member being adapted to engage the enlarged end turn hereinbefore described. A plurality of screws 26 are provided to secure the cap member 24 against the outer end of the tubular casing 8, the cap 24 being of such outer contour as to present a finished and pleasing appearance.

When the cap member 24 is placed against the outer end of the casing 9 in substantially the position illustrated in Fig. 1, it presses the insulating washer 23 against the outwardly extending portion of the contact member 15 to prevent the contact terminal structure, comprising the tubular

member 10, the contact member 12 located therein and the contact members 14 and 15 mounted thereon from moving longitudinally in an outwardly direction. The location of the clamping ring 18 on the tubular member 10 and its longitudinal dimensions are such that, when the contact-terminal structure hereinbefore described is in its proper operative position in the tubular casing 9, the inner edge of the clamping ring 18 engages a shoulder 27 provided for that purpose in the axial opening in the tubular casing 9.

It may be noted that the device embodying my invention comprises a curling-iron-plug connector comprising relatively few and simple parts in which the casing members may be made of molded material. The inner construction is such that proper operative relation of the parts to each other is maintained without the use of any parts other than the contact members themselves.

The device embodying my invention provides a swiveling type of plug connector which may be easily and quickly removed and inserted in its operative location in the handle member of the curling iron. As the contact members are located substantially concentrically and, as the tubular casing extends beyond the elongated members to properly protect the same, there is no danger of the operator experiencing a shock while handling the plug.

Various modifications may be made in the device embodying my invention without departing from the spirit and scope thereof and I desire that only such limitations shall be placed thereon as are imposed by the prior art or are specifically set forth in the appended claims.

I claim as my invention:

1. A connecting plug for an electrically heated implement comprising a cylindrical insulating member having a circumferential groove near one end and an axial opening of varying diameter therethrough, a tubular contact terminal located in said axial opening, a pair of elongated oppositely spaced contact members located on said cylindrical insulating member, a ring located outside of said spaced contact members over said circumferential groove to resiliently clamp said members to said cylindrical member, supply circuit conductors, a single means for securing said tubular contact terminal in said insulating member and for connecting one of said supply circuit conductors thereto, an insulating casing surrounding all of said parts and means encircling said supply circuit conductors and operatively secured to said casing for maintaining all of said parts in their operative positions in said casing.

2. A connecting plug for an electrically heated implement comprising a substan-

tially cylindrical insulating casing having an axial opening of varying diameter extending therethrough, a tubular insulating member, a plurality of longitudinally extending elongated contact members located on said tubular member, and a clamping ring adapted to maintain said elongated contact members in their operative position on said tubular member and to co-operate with said casing to prevent longitudinal movement of said tubular member and said contact members in one direction relatively to said casing.

5 In testimony whereof, I have hereunto subscribed my name this 23 day of May, 1921.

FRANK F. FORSHEE.
